CLAIM

The ornamental design for a tile lippage [threaded] post, as shown and described.

DESCRIPTION

[FIG. 1 is a bottom perspective view of a tile lippage threaded post incorporating my new design;]
[FIG. 2 is a top perspective view thereof;]
[FIG. 3 is a bottom plan view thereof;]
[FIG. 4 is a top plan view thereof;]
[FIG. 5 is a left side elevation view thereof;]
[FIG. 6 is a right side elevation view thereof;]
[FIG. 7 is a front elevation view thereof; and,]
[FIG. 8 is a rear elevation view thereof.]

The sole FIGURE is a top perspective view of a tile lippage post.
The broken lines and unshaded regions in the [drawings illustrate] drawing illustrates portions of the tile lippage [threaded] post that form no part of the claimed design.

1 Claim, 5 Drawing Sheets

Matter enclosed in heavy brackets [ ] appears in the original patent but forms no part of this reissue; matter printed in italics indicates the additions made by reissue.

Related U.S. Application Data

continuation-in-part of application No. 29/552,045, filed on Jan. 20, 2016, now Pat. No. Des. 778,709, which is a continuation-in-part of application No. 14/823,085, filed on Aug. 11, 2015, now Pat. No. 9,279,259, which is a continuation-in-part of application No. 14/718,131, filed on May 21, 2015, now Pat. No. 9,322,185.
